UNITED STATES PATENT OFFICE.

SVEN AXEL ALLAN STENBERG, OF LOS ANGELES, CALIFORNIA.

DESIGN FOR A HATPIN.

57,388.

Specification for Design. Patented Mar. 15, 1921.

Application filed April 22, 1920. Serial No. 375,905. Term of patent 14 years.

To all whom it may concern:

Be it known that I, SVEN AXEL ALLAN STENBERG, a citizen of Sweden, residing at Los Angeles, in the county of Los Angeles and State of California, have invented a new, original, and ornamental Design for Hatpins, of which the following is a specification, reference being had to the accompanying drawing, forming part thereof.

The figures, showing my new design, are a vertical side view, and a top plan view, of a mounting pin or frame, constructed to support an eucalyptus pod, or imitation thereof.

I claim:

The ornamental design for a hatpin, as shown.
